(57) **CLAIM**

(21) Appl. No.: **29/262,358**

The ornamental design for a sliding lens shutter cover for projector as shown and described.

(22) Filed: **Jul. 3, 2006**

DESCRIPTION

(30) **Foreign Application Priority Data**

Mar. 3, 2006 (JP) 2006-005348

FIG. 1 is a perspective view of a sliding lens shutter cover for projector showing our new design;

(51) **LOC (8) Cl.** **16-02**

FIG. 2 is a front view thereof;

(52) **U.S. Cl.** **D16/235; D16/221**

FIG. 3 is a rear view thereof;

(58) **Field of Classification Search** D16/200-205,
D16/208, 213, 221, 225, 229, 230, 231, 234,
D16/217, 219, 235; D21/514; D25/47; 353/70,
353/88, 96, 100, 101, 115, 119, 122

FIG. 4 is a left-side view thereof;

See application file for complete search history.

FIG. 5 is a right-side view thereof;

(56) **References Cited**

FIG. 6 is a top view thereof;

U.S. PATENT DOCUMENTS

FIG. 7 is a bottom view thereof; and,

D225,280 S * 11/1972 Conner D16/219
D396,870 S * 8/1998 Ohwada D16/202
D398,321 S * 9/1998 Iida D16/230

FIG. 8 is a perspective view thereof.

The broken lines are for illustrative purposes only and form no part of the claimed design.
